TOOTH CLEANING DEVICE

Michael J. McCaughley, Brooklyn, N. Y.

Application July 21, 1945, Serial No. 606,377

4 Claims. (Cl. 15—172)

1

This invention relates to tooth cleaning devices in general and to the process for making parts thereof.

Among the objects of the present invention, it is aimed to provide a tooth cleaning device which will enable the user, more particularly the layman, effectively to clean his own teeth in such a manner that he will be able to intimately engage the accessible surfaces of his teeth and those surfaces inaccessible to the bristles of the conventional tooth brush.

It has been found as an instance that the conventional practice employed by an individual to clean his own teeth is by means of a brush or the like. In this practice, it is recognized by the dental profession that the bristles of a brush, even when used by a careful individual, may gain access to only limited surfaces of the teeth of the average individual and that extensive surfaces of the teeth are practically inaccessible to the bristles of a tooth brush. In the next place, it has also been found that the formation of tartar results from films or mucin deposits on the teeth, which films or deposits are not effectively removed by the bristles of the conventional tooth brush and if removed at all, are only partially removed where the bristles of the brush of a user have free access to such films or mucin deposits.

Due to the fact that extensive surface areas of the teeth of the ordinary individual are practically inaccessible to the bristles of a conventional tooth brush, it has been impossible entirely to remove such films or mucin deposits, and in turn, properly to clean the teeth by the conventional tooth brush.

To this end, it is an object to produce an improved tooth cleaning device which will make it possible for the average individual effectively to remove objectionable films, food debris and mucin from the surfaces of the teeth which are not ordinarily accessible to the bristles of the conventional tooth brush, as well as to those surfaces which are readily accessible.

The dental profession has also recognized that the daily massaging of the gums is very important to maintain healthy gums and to prevent, retard, and in some cases actually to eliminate certain types of gum diseases. To this latter end, it is also an object of the present invention to provide an improved tooth cleaning device by means of which the average individual may effectively clean and polish his teeth as well as to massage his gums by one and the same device.

It is also an object of the present invention to provide an improved process for making tooth

2

cleaning pads or buffers constituting a part of the tooth cleaning device.

These and other features, capabilities and advantages of the invention will appear from the subjoined detail description of one specific embodiment thereof illustrated in the accompanying drawings, in which

Fig. 1 is a side elevation of the device shown in position, in full lines, to clean the inner surface of an upper tooth, and in dash and dot lines in position to clean the inner surface of a lower tooth;

Fig. 2 is a fragmental side elevation of the device partly in section and enlarged relative to full scale;

Fig. 3 is a fragmental end elevation of the device drawn to the same scale as that shown in Fig. 2;

Fig. 4 is a section on the line 4—4 of Fig. 2;

Fig. 5 is a perspective of a cleaning element or pad slightly enlarged relative to the scale of the device shown in Fig. 2.

The cleaning device consists essentially of a handle 1 composed of any suitable substance such as wood, plastic and the like, having an internally threaded chamber 2 and in the present instance two receding bases 3 and 4. The internally threaded chamber 2 screw-threadedly receives the chambered support or shank 5 of the supporting element 6 having the rectangular recesses or openings 7 therein to receive the knurled control sleeve 8 screw-threadedly mounted on the shank 9 which is movable in the chamber 10 of the support 6. The shank 9 has formed in its outer end a thin flexible rod portion 11 which is pivotally connected by the pin 12 in the bearings 13 and 14 at one end of the chambered holder 15, in the present instance. The holder 15 is substantially rectangular in cross-section, having an upper wall 16, a lower wall 17 and two lateral walls 18 and 19. The walls 18 and 19, see Fig. 4, are inclined to one another and have in the present instance recesses removed from the bearings 13 and 14 to receive the pins 20 and 21 at the ends of the arms 22 and 23 respectively, preferably consisting of thin rods extending upwardly from the outer end of the support 6. Preferably the rod portion 11 is flexible for the purpose hereinafter set forth.

With the exception of the handle 1, preferably all of the other elements so far described, including the support 6, sleeve 8, shank 9, portion 11, arms 22 and 23, and holder 15 are composed of metal.

The holder 15 is formed to receive removable

cleaning elements or pads such as the pad 24 in Fig. 5. This pad 24 preferably has two side walls 25 and 26 which incline relative to one another. The pad 24 also has two walls 27 and 28 which are substantially parallel to one another although they may also incline relative to one another. The wall 27 continues at its ends into the receding faces 29 and 30 and the wall 28 in turn continues at its ends in the receding walls 31 and 32. The walls 29 and 31 incline to one another and terminate in the blunt end 33, while the receding faces 30 and 32 in turn incline toward one another and terminate in the blunt end 34. Pads such as the pad 24 are removable from the holder 15 and are intended to be discarded after use for obvious reasons. Furthermore, the pads 24 are formed of such material that they can be produced at low cost to enable the user to discard them after each treatment at comparatively low cost. To this end, it has been found that excellent results have been achieved when the blocks were made of some inexpensive substance, such as wool felt or the like, having a surface nap which will readily remove all food debris, films and mucin from the surfaces of the teeth by a slight rubbing or polishing action. Since felt, as is also the case with cotton, has a great affinity for water, the pads are preferably immersed in a water resisting solution. When the material used is wool felt, it has been found that excellent results have been achieved when the pads are dipped in a solution consisting of alcohol, resins such as Manila resin, phenol crystals and a flavoring substance such as aromatic peppermint, this solution forming a water resistant coating that is in addition antiseptic and also pleasant to the taste of the user. It has also been found to advantage to dip the pads 24 initially in a solution of alcohol and resin to form a water resistant coating, with or without a flavoring substance such as aromatic peppermint, and after the coating has dried, then to dip the so formed pads in an antiseptic solution composed either of chlorine or metaphen.

The flavoring substance is added primarily to offset the taste of the resinous gum, which is objectionable to the average taste.

The solution for forming the water resistant coating preferably consists of three parts by weight of alcohol of 190 proof, to one part by weight of a resinous gum such as Manila resin. The phenol crystals when added to the solution forming the water resistant coating should not exceed five percent by weight of the entire solution, and the flavoring substance, if aromatic peppermint is used, need not exceed one tablespoon to a pound of the solution for forming the water resistant coating.

If the antiseptic solution is to be used after the water resistant coating has been formed and dried, then a chlorine solution or metaphen solution is preferably used.

While it is an object to produce these pads 24 at such low cost so that they may be thrown away after having been used for a single treatment, it is obvious that they may be sterilized by any method of cold sterilization not harmful to the tissues and thus be used a number of times, thereby greatly reducing the cost of this device which would only be nominal to begin with.

In operation, the pad 24 is initially pressed into the holder 15 until it frictionally is anchored in place and then depending upon the teeth to be treated, the sleeve 8 is rotated to position the pad 24 at the proper angle relative to the support 6.

As an instance, if the palatal or inner face of an upper tooth is to be polished, see the full line position of the device in Fig. 1, the pad 24 may form an angle of substantially 90° with the support 6. If, on the other hand, the lingual or inner face of a lower tooth is to be polished, see the dash and dot line position of the device in Fig. 1, then the same may be used to advantage when the pad 24 is adjusted to form an angle of about 30° with the support 6. Preferably either the rod 11 as one element or the arms 22 and 23 as the other element are flexible, that is, composed of a yieldable material so that the rotation of the sleeve 8 will enable the holder 15 to assume different angles relative to the support 6. Preferably the rod 11 is composed of a yieldable material although obviously either the rod 11 may be composed of yieldable material or else the rods 22 and 23 be composed of yieldable material, or finally, all three rods 11, 22 and 23 may be composed of yieldable material so long as they will cooperate with the sleeve 8 and shank 9 to adjust the angular position of the holder 15 relative to the support 6. For this reason, depending upon the thickness of the rods 11, 22 and 23, and the yieldability of the material, various lengths may be selected for the distance of the rods 11, 22 and 23 between the end of the support 6 and the holder 15. Excellent results have been achieved when the rods 22 and 23 are about three-fourths of an inch from the support 6 to the pivot pins 20, 21 and the diameter of the rod 11 does not exceed one-sixteenth of an inch, substantially as shown in Fig. 1.

While obviously the size and shape of the pads 24 may vary without departing from the general spirit of the invention, it may be pointed out that excellent results have been achieved when the pads are approximately five-eighths of an inch in length and about one-fourth of an inch in width and about one-eighth of an inch in thickness at the thickest part.

In place of wool felt, the pad 24 may also be composed of artificial silk, rayon, cotton or fabric, in which case, preferably it should also be conformed as illustrated in Fig. 5, it having been found that substances such as wool felt or other fabrics are sufficiently rigid effectively to clean and polish teeth and also to massage gums as compared as an instance to a metal which might abrade or injure the enamel of a tooth when scraped across a tooth surface and also injure the skin of a gum if reciprocated across a gum in the manner that a felt pad would be manipulated to massage a gum. In place of wool felt, any other suitable felt or like fabric may be used and preferably provided with a moisture-proof coating or immersed in a moisture-proof solution if water or moisture would cause the fibers to disintegrate.

It is obvious that various changes and modifications may be made to the details of construction and to the steps of the process without departing from the general spirit of the invention as set forth in the appended claims.

I claim:

1. In a tooth cleaning device, the combination of a chambered support, an elongated shank mounted for longitudinal movement in said support, a control sleeve screw-threadedly connected to said shank securely to anchor the shank and adjust the position of the same, there being openings in said support to position said sleeve and afford access to the same, a chambered holder pivotally connected to one end of said support and to one end of said shank, the pivotal connections

between said holder on the one hand and said handle and shank on the other hand being spaced from one another so that longitudinal movement of said shank relative to said support will vary the angular relationship of said holder to said support, and a tooth cleaning device removably mounted in the chamber of said holder.

2. In a tooth cleaning device, the combination of a handle, an elongated chambered support secured to said handle, a shank slidably mounted for longitudinal movement in the chamber of said support, a sleeve screw-threadedly mounted on said shank securely to anchor the same, there being openings in said support to position said sleeve and afford access to same, two arms extending from said support, said shank having a flexible rod portion extending from said shank, a holder pivotally connected to the free end of said rod portion and to the free ends of said arms, the pivotal connection of said arms being in alinement with one another and being spaced from the pivotal connection of said rod portion, and a cleaning device removably mounted in said holder.

3. In a tooth cleaning device, the combination of a handle, an elongated chambered support secured to said handle, a shank mounted for longitudinal movement in the chamber of said support, a sleeve screw-threadedly mounted on said shank, there being openings in said support to position said sleeve and afford access to same, two arms extending from said support, said shank having a flexible rod portion extending from said shank, a holder pivotally connected to the free end of said rod portion and to the free ends of said arms, the pivotal connection of said arms being in alinement with one another and being spaced from the pivotal connection of said rod

portion, and a cleaning device removably mounted in said holder, the walls of said holder being tapered, and the sides of said cleaning device being tapered, and conforming to the chamber of said holder.

- 5 4. In a tooth cleaning device, the combination of a handle, an elongated chambered support secured to said handle, a shank mounted for longitudinal movement in the chamber of said support, a sleeve screw-threadedly mounted on said shank, there being openings in said support to position said sleeve and afford access to same, two arms extending from said support, said shank having a flexible rod portion extending from said shank, a holder pivotally connected to the free end of said rod portion and to the free ends of said arms, the pivotal connection of said arms being in alinement with one another and being spaced from the pivotal connection of said rod portion, and a cleaning device removably mounted in said holder, said holder being rectangular in cross-section with its side walls inclined to one another, and the sides of said cleaning device being inclined to one another, and conforming to 10 the chamber of said holder.
